UNITED STATES PATENT OFFICE.

LOUIS C. NEFF, OF BROOKLYN, NEW YORK.

COLLAR-SPREADER.

1,269,205.

Specification of Letters Patent. Patented June 11, 1918.

Application filed April 7, 1915. Serial No. 19,799.

To all whom it may concern:

Be it known that I, LOUIS C. NEFF, a citizen of the United States, residing at the borough of Brooklyn, in the city, county of 5 Kings and State of New York, have invented certain new and useful Improvements in Collar-Spreaders, of which the following is a specification, reference being had therein to the accompanying drawings, which form 10 a part thereof.

My invention relates to collar spreaders for giving form to the band of a lay down collar, and more particularly to an implement adapted for use in so forming the band 15 of a laundried collar as to separate the band and the face sufficiently to allow a free slippage of the neck-tie within the folded collar after the collar has been attached to the neck-band of a shirt.

20 In lay down collars as ordinarily manufactured, the pattern of the face is so laid out as to avoid unnecessary waste of the cloth in making the collar. The result is that in lay down collars, the band and the 25 face set so closely together that when the band is attached to the neck-band of the shirt, a tie disposed between said band and the said face, will bind sufficiently to make a movement of the tie difficult. This binding of the tie within the fold of the collar 30 is not only a cause of annoyance, but results in a disarrangement of the collar and frequently in the tearing of the collar at the front corners, or the tearing of the tie itself.

35 By means of an implement made in accordance with my invention, an ordinary lay down collar wherein the band and face are set sufficiently close together to offer substantial resistance to the free movement of 40 the tie, may have the band so constructed at different points thereof as to spread the collar in a manner to increase the space between the band and the face to an extent to afford ample clearance for the neck-tie and 45 permit the free movement thereof. This implement is so constructed that it will take up the material of the band in a manner to shorten the band sufficiently to secure the desired spreading effect without interfering 50 with the flexibility of the band, or breaking down the textile so as to present rough spots or cause the cracking or mutilation of the collar upon its being re-laundried.

Preferably a collar spreader made in ac-

cordance with my invention is so constructed 55 as to be readily adapted for hand use, thus enabling the wearer to quickly and conveniently form the band just prior to the attachment of the collar to the neck-band of the shirt. This avoids likelihood of the 60 band losing its form prior to the use of the collar.

The forming of the band of the collar by means of a spreader made in accordance with my invention does not result in any 65 permanent alteration in the collar, the portion of said band formed up by the tool, being restored to its normal relation when the collar is re-laundried. The tool is so constructed as to vary its operative effect 70 upon the band in a manner to cause the greatest reduction in the diameter to be at the lower edge of the band. The coöperating opposed members are so constructed and arranged as to prevent forming of the 75 band to an extent to exceed the necessary construction, and are so constructed and associated as to permit the forming up of the band without binding the material in a way to cause the application of pressure thereto 80 to stretch or tear the fabric. This characteristic is essential to my invention as the constriction of the band results from the movement of the entire band to an extent determined by the number and depth of the 85 crimps or corrugations placed in the band.

The invention consists primarily in a collar spreader consisting of oppositely disposed coöperating members, one of said members having an opening therein and the 90 other member having a projection adapted to enter said opening, the dimensions of said opening being such in relation to the member adapted to enter same as to permit the sliding of the fabric of the band between said 95 members upon the closing of said members; and in such other novel features of construction and combination of parts as are herein-after set forth and described and more particularly pointed out in the claims hereto 100 appended.

Referring to the drawings,

Figure 1 is a perspective view of a collar having a plurality of crimps or corrugations formed in the band thereof by an implement 105 made in accordance with my invention so as to spread the band away from the face of the collar;

Fig. 2 is a side elevation of the preferred form of a hand implement embodying my invention;

Fig. 3 is a front view thereof upon a larger scale with the jaws separated and the handle grips omitted;

Fig. 4 is a cross section of the jaws closed showing the position of the collar therein;

Fig. 5 is a view partly in section of a modified form of the invention showing the use of parallel jaws; and

Fig. 6 is a perspective view partly in section of a portion of the jaw construction shown in Fig. 5.

15 Like letters refer to like parts throughout the several views.

A collar spreader made in accordance with my invention comprises oppositely disposed coöperating members adapted to have the edge of the band inserted therebetween to permit the application of pressure to the band through said members in a manner to form a crimp or corrugation in the band extending perpendicularly to the edge thereof and terminating at a point adjacent the fold connecting it and the face. The male and female portions are so constructed as to prevent the clamping of the collar therebetween and to permit that free movement of the fabric, incidental to the formation of said crimp or corrugation.

An implement embodying the essential characteristics of my invention, may take a variety of forms, two of which are illustrated 35 in the accompanying drawings.

In the form of the invention shown in Figs. 2, 3 and 4, *a* and *b* indicate lever handles pivoted at *c* and having oppositely disposed jaw extensions *d* and *e* constituting coöperating members for engaging and forming corrugations in the collar band. The jaw *d*, forming an extension of the lever handle *a* has an opening *d'* therethrough formed by the parallel sides of the jaw, said opening extending through the outer end of said jaw. The upper and inner edges of the jaw *d* about the opening *d'*, are chamfered or rounded as shown at *d²* and at *d³* I provide bearing surfaces adapted to act as a stop for limiting the operative effect of the implement upon the collar band.

The jaw *e*, forming an extension of the lever handle *b* is provided with a projection *e'* adapted to enter the opening *d'* and force 55 the collar band thereinto, in a manner to give such form thereto as to crimp or corrugate the band to take up, or gather, it for the purpose of shortening the radius of said band, when the collar is applied to the neck-band of a shirt. The length of this projection coincides with that of the opening *d'* and its top is so rounded, as at *e²*, to prevent the cutting of the collar band when the jaws are closed thereupon. The width of the 60 projection *e'* is sufficiently less than that of

the opening *d'* to afford clearance between said projection and the sides of said opening, sufficient to receive the fabric of the collar without any binding action therebetween.

Upon each side of the projection *e'* are shoulders *e³* adapted to engage the bearing surfaces *d³* upon the jaw *d*.

The said shoulders and bearings adjacent the pivot *c* are so spaced apart as to avoid any shearing action thereby and to cause the stop action to result only upon the completion of the closing of the jaws.

One of said jaws as *d* is provided with a gage shoulder *f* for limiting the extent to 80 which the collar band may be projected within said jaw.

Inasmuch as it is desirable to constrict the free edge of the band to a greater extent than the upper portion thereof, I so construct the coöperating members as to cause that portion of the jaw adjacent the edge to more deeply crimp or corrugate the band than those portions operative farther away from said edge. In the form of the invention shown in the drawings, I secure this result by forming the projection *e'* of a gradually increased height toward the pivot *c*.

In the form of the invention shown in 95 Figs. 5 and 6 the construction is substantially like that shown in Figs. 2 to 4 with the exception that instead of using a tongs construction of the lever handles and jaws, I employ an ordinary parallel jaw move- 100

ment as ordinarily employed in pliers, punches and similar tools. In this form of the invention the handles are indicated at *a'* and *b'* pivotally connected at *c'*. The handle *a'* is pivotally connected with the female jaw *g*, which jaw slides upon a pivot *g'* carried by the handle *b'*. A spring *b²* carried by the handle *b'* and acting upon the jaw *g* serves to normally open said jaws.

The male jaw *H* is pivotally connected 11 with the lever connected with the lever handle *b'* and has sliding movement upon the pivot *h'* carried by the handle *a'*.

The female jaw *g* has a troughed opening *g²* therein, which opening extends through the forward end of said jaw and is rounded at the bottom thereof.

The jaw *h* is provided with a projection *h²* graduated in height and formed in the same manner as the projection *e'* in the form of the invention shown in Figs. 2 and 4. The troughed opening *g²* varies in depth in accordance with the variance in height of the projection *h²*.

The edges of the jaw *g* about the trough *g²* are chamfered, or rounded, as shown at *g³* and have stop bearings *g⁴* presented toward the jaw *h*.

The jaw *h* is provided with the shoulders *h³* upon opposite sides of the projection *h²* 12

adapted to coöperate with the stop bearings g^4 . One of said jaws as h is provided with a gage i for preventing the collar being inserted between the projecting ends of the lever handles a' and b' .

The dimensions of the projection h^2 and of the trough g^2 are so proportioned as to afford clearance between the walls of said trough and the face of said projection to permit a free sliding movement of the collar band therein as the jaws are closed.

The operation of a collar spreader made in accordance with my invention is substantially as follows:—

15 The edge of the band of a laundried collar is inserted between the male and female members of the implement so as to cause the male member to force the band into the female member in a manner to take up the 20 band from a point at the edge thereof along a line toward the point of connection with the face. This forms a crimp or corrugation in the band of gradually decreasing depth toward the point of connection with the face 25 of the collar. Enough pressure is exerted upon the band by these members to give a sufficiently firm set thereto to insure the formation of the crimp, without, however, imparting any stretch to the fabric of the band 30 or cracking or mutilating it in any way. The apex of the crimp or corrugation should be presented inwardly of the band so that the fabric entering into said crimp, or corrugation, will not occupy any portion of the 35 space in which the neck-tie must move. The crimps or corrugations thus formed do not give a permanent set to the band and when the collar is re-laundried the band will again become perfectly flat and of substantially 40 the same length as though the implement had not been used thereon.

The number and location of the crimps or corrugations placed in the collar will vary according to the requirements of different

45 collars. The effect of these corrugations is to shorten the radius of the band from the edge thereof to a point sufficiently close to the line of its attachment to the face, to insure ample clearance for the tie. At the 50 same time if the number of crimps taken in the band be sufficiently great to shorten the band to an extent too great to permit its convenient application to the shirt-band, the band, nevertheless, will possess sufficient 55 flexibility to give sufficiently to permit the collar to be conveniently buttoned upon the front collar button. The increased depth of the crimp or corrugation along the line of the collar buttons will permit this extension 60 of the band without materially reducing the clearance at the point of the collar where the tie is located.

The constriction of the band adjacent the edge thereof will have the effect of spreading the band and the face away from each

other and yet when the collar is on, the presence of these crimps or corrugations will not in any way change the set of the collar.

In the forms of the invention shown the male jaw is inserted between the band and the face at the desired points and the jaws are closed upon the collar until the stop bearing and shoulder coöperate, through the fabric of the collar, in a manner to arrest further movement of the jaws. The formation of the opening and the coöperating projection adapted to enter same is such that as the jaws are closed, the band will be drawn therebetween thus preventing the stretching of the fabric and causing the gathering or taking up of the material of the band in a manner to secure the desired shortening effect thereupon.

The gage is merely for limiting the extent to which the collar may be projected between the jaws.

The graduated height of the projection causes that desired greater depth at the edge of the band.

In the form of the invention shown in Fig. 2, clearance between the bearing faces and shoulders prevents the clamping of the collar before the maximum crimp has been made therein.

I believe it to be broadly new to provide a mechanism whereby the band of a collar may be shortened in a manner to prevent the binding of the tie between the band and the face, said shortening involving no distortion or mutilation of the collar and I intend to claim such broadly.

The construction and arrangement of the coöperating members may be varied indefinitely, the two forms of hand tools being shown in the accompanying drawings, not as defining the limits as to the form which this tool may take, but for illustrating two forms of the tool which may be conveniently used.

It is not my intention to limit the invention to the two forms shown, however.

Having described the invention, what I claim as new and desire to have protected by Letters Patent is:—

1. A collar spreader consisting of oppositely disposed coöperating members, one of said members having an opening therein, and the other of said members having a projection adapted to enter said opening, the width of said opening being greater than that of said member adapted to enter same whereby the fabric of the collar band is permitted to slide between said members as said projection enters said opening.

2. A collar spreader consisting of oppositely disposed coöperating members, one of said members having an elongated opening therein, and the other of said members having a projection of gradually increased height toward one end thereof adapted to

enter said opening, the width of said opening being greater than that of said member adapted to enter the same whereby the fabric of the collar band is permitted to slide between said members as said projection enters said opening.

3. A collar spreader consisting of oppositely disposed coöperating members, one of said members having an opening therein, and the other of said members having a projection adapted to enter said opening, the width of said opening being greater than that of said member adapted to enter same whereby the fabric of the collar band is permitted to slide between said members as said projection enters said opening, said members being provided with oppositely disposed surfaces and adapted to limit the extent of penetration of said projection into said opening.

4. A collar spreader consisting of oppositely disposed coöperating members, one of said members having an elongated opening therein and bearing surfaces upon opposite sides thereof and the other of said members having a projection of gradually increased height toward one end thereof adapted to enter said opening and stop shoulders upon opposite sides of said projection adapted to engage said bearing surfaces upon the other member and limit the extent of penetration of said projection into said opening, the width of said opening being greater than that of said member adapted to enter the same whereby the fabric of the collar band is permitted to slide between said members as said projection enters said opening.

5. A collar spreader consisting of oppositely disposed coöperating members, one of said members having an elongated opening therein and the other of said members having a projection of gradually increased height toward one end thereof adapted to enter said opening, the width of said opening being greater than that of said member adapted to enter the same and the edges of said opening and the top of said projection being rounded whereby the fabric of the collar band is permitted to slide between said members as said projection enters said opening.

6. A collar spreader consisting of oppositely disposed coöperating members, one of said members having an elongated opening therein and bearing surfaces upon opposite sides thereof and the other of said members having a projection of gradually increased height toward one end thereof adapted to enter said opening and stop shoulders upon opposite sides of said projection adapted to engage said bearing surfaces upon the other member and limit the extent of penetration of said projection into said opening, the width of said opening being greater than

that of said member adapted to enter the same and the edges of said opening and the top of said projection being rounded whereby the fabric of the collar band is permitted to slide between said members as said projection enters said opening.

7. A collar spreader consisting of oppositely disposed coöperating members, one of said members having an opening therein and bearing surfaces upon opposite sides thereof, and the other of said members having a projection adapted to enter said opening and stop shoulders upon opposite sides of said projection adapted to engage said bearing surfaces upon the other member and limit the extent of penetration of said projection into said opening, the width of said opening being greater than that of said member adapted to enter same whereby the fabric of the collar band is permitted to slide between said members as said projection enters said opening, said members being provided with oppositely disposed surfaces adapted to limit the extent of penetration of said projection into said opening.

8. A collar spreader consisting of oppositely disposed coöperating members, one of said members having an elongated opening therein and bearing surfaces upon opposite sides thereof and the other of said members having a projection of gradually increased height toward one end thereof adapted to enter said opening and stop shoulders upon opposite sides of said projection adapted to engage said bearing surfaces upon the other member and limit the extent of penetration of said projection into said opening, the width of said opening being greater than that of said member adapted to enter the same and the edges of said opening and the top of said projection being rounded whereby the fabric of the collar band is permitted to slide between said members as said projection enters said opening, said members being provided with oppositely disposed surfaces adapted to limit the extent of penetration of said projection into said opening.

9. A collar spreader consisting of oppositely disposed jaws, pivotally connected lever handles adapted to open and close said jaws, one of said jaws having an opening therein with bearing surfaces upon opposite sides of said opening, and the other of said jaws having a projection thereon adapted to enter said opening and stop shoulders adapted to engage said bearing surfaces whereby the extent of penetration of said projection into said opening is limited, the width of said projection being less than that of said opening whereby the fabric of the band of a collar is permitted to slide between said jaws while they are being closed to prevent the breaking or stretching of said fabric.

10. A collar spreader consisting of oppositely disposed jaws, pivotally connected lever handles adapted to open and close said jaws, one of said jaws having an opening 5 therein with bearing surfaces upon opposite sides of said opening, and the other of said jaws having a projection of gradually increasing height toward the point of pivotal connection of said handles adapted to enter 10 said opening and stop shoulders adapted to engage said bearing surfaces whereby the extent of penetration of said projection into said opening is limited the width of said projection being less than that of said opening 15 whereby the fabric of the band of a collar is permitted to slide between said jaws while they are being closed to prevent the breaking or stretching of said fabric.

11. A collar spreader consisting of oppositely disposed jaws, pivotally connected lever handles adapted to open and close said jaws, one of said jaws having an opening therein with bearing surfaces upon opposite sides of said opening, and the other of said 20 jaws having a projection thereon adapted to enter said opening and stop shoulders adapted to engage said bearing surfaces whereby the extent of penetration of said projection into said opening is limited, the width of said projection being less than that of said opening whereby the fabric of the band of a collar is permitted to slide between said jaws while they are being closed 25 to prevent the breaking or stretching of said fabric and a stop gage for accurately positioning the collar band with relation to 30

35

said jaws and the pivotal connection of said members.

12. A collar spreader consisting of pivotally connected lever handles, a jaw carried by each of said handles and projecting beyond the point of pivotal connection thereof, one of said jaws having parallel side bars spaced apart, leaving an opening therebetween and forming bearing surfaces presented toward the other jaw, the inner edges of said bars being rounded, and the other of said jaws having a projection of gradually increasing height toward said point of pivotal connection of said handles, and shoulders adapted to coöperate with said bearing surfaces upon said other jaw, said projection being adapted to enter the opening between said jaws and being of a width less than the distance between the side bars of the other jaw whereby the fabric of a collar is permitted to slide between said jaws as they are being closed and breaking or tearing of the fabric is prevented, said shoulders and said bearing surfaces being spaced apart adjacent the point of pivotal connection of said levers whereby shearing action upon said fabric is prevented, and a gage stop carried by one of said jaws adjacent said point of pivotal connection.

In witness whereof, I hereunto affix my signature in the presence of two subscribing witnesses this 6th day of April, 1915.
